US0D1090523S

(12) **United States Design Patent** (10) Patent No.: **US D1,090,523 S**
(45) Date of Patent: ** Aug. 26, 2025

(54) **INTERACTIVE KIOSK**

(71) Applicant: **LG ELECTRONICS INC.**, Seoul (KR)

(72) Inventors: **Hyeyoung Hong**, Seoul (KR); **Seungdon Lee**, Seoul (KR); **Jiyeon Lee**, Seoul (KR); **Yoonkyeong Lee**, Seoul (KR)

(73) Assignee: **LG ELECTRONICS INC.**, Seoul (KR)

(**) Term: **15 Years**

(21) Appl. No.: **35/522,525**

(22) Filed: **Mar. 28, 2024**

(80) **Hague Agreement Data**

Int. Filing Date: **Mar. 28, 2024**

Int. Reg. No.: **DM/238717**

Int. Reg. Date: **Mar. 28, 2024**

Int. Reg. Pub. Date: **Oct. 4, 2024**

(30) **Foreign Application Priority Data**

Nov. 14, 2023 (KR) 30-2023-0045224

(51) **LOC (15) Cl.** **14-02**

(52) **U.S. Cl.**

USPC **D14/307**

(57) **CLAIM**

The ornamental design for an interactive kiosk as shown and described.

DESCRIPTION

1. Interactive kiosk

1.1 : Perspective

1.2 : Back perspective view

1.3 : Front

1.4 : Back

1.5 : Left

1.6 : Right

1.7 : Top

1.8 : Bottom

1.9 : Reference

1.10 : Reference

1.11 : Reference

The broken lines indicate portions of the article that form no part of the claimed design; reproduction 1.9 is a reference view of the state in use showing the height of the claimed design is adjusted; reproduction 1.10 is reference view of state in use showing the display unit is rotated horizontally; reproduction 1.11 is a reference view of state in use showing accessories are installed on both sides; broken lines in reproduction 1.11 are for the purpose of illustrating environment only and form no part of the claimed design.

1 Claim, 11 Drawing Sheets
